UNITED STATES PATENT OFFICE.

EMIL F. BEHRENDT, OF FOLEY, MINNESOTA.

WINDOW-SASH STOP AND FASTENER.

1,333,599.

Specification of Letters Patent. Patented Mar. 16, 1920.

Application filed July 9, 1919. Serial No. 309,616.

To all whom it may concern:

Be it known that I, EMIL F. BEHRENDT, a citizen of the United States, residing at Foley, in the county of Benton and State 5 of Minnesota, have invented certain new and useful Improvements in Window-Sash Stops and Fasteners; and I do hereby declare the following to be a full, clear, and exact description of the invention, such as 10 will enable others skilled in the art to which it appertains to make and use the same.

My invention has for its object to provide an extremely simple and highly efficient sash stop and fastener, and to this end it consists 15 of the novel devices and combinations of devices hereinafter described and defined in the claim.

In the accompanying drawings, which illustrate the invention, like characters indicate 20 like parts throughout the several views.

Referring to the drawings:

Figure 1 is a perspective view showing a pair of the improved sash stop and fastener 25 applied to a swinging storm sash and window frame having upper and lower sliding sashes and adjusted to hold the storm sash open;

Fig. 2 is a central vertical section of the 30 parts, as shown in Fig. 1;

Fig. 3 is a fragmentary detail view on an enlarged scale showing the invention adjusted to lock the storm sash closed;

Fig. 4 is a detail view with some parts 35 sectioned on the line 4—4 of Fig. 3;

Fig. 5 is a detail view of the clamping sleeve;

Fig. 6 is a detail view in section taken on the line 6—6 of Fig. 5; and

Fig. 7 is a perspective view of the sill bracket.

The numeral 8 indicates a building having a window opening in which is secured a window frame 9, having mounted therein 45 upper and lower vertical sliding sashes 11. A storm sash 11 is secured at its upper end by hinges 12 to the upper end of the window frame for outward swinging movement. As shown, the storm sash 11 is attached to the 50 window frame 9 by a pair of the improved sash stops and fasteners, and as both of these sash stops and fasteners are identical the one with the other, the description of the one will suffice for the other.

55 The improved sash stop and fastener

comprises a sill bracket 13, a sash bracket 14, a rod 15 and a link 16. The sill bracket 13 is secured to the sill of the window frame 9 by a pair of screws 17, and is provided with a pair of laterally spaced upwardly projecting ears having formed therein a pair of aligned bores 18. A lock shoulder 19 is formed in one of the ears of the sill bracket 13. The sash bracket 14 is secured by screws 20 to the frame of the storm 65 sash 11 at one of the lower corners thereof, and is provided with a recess 21.

A spring pressed detent 22 is mounted in the recess 21 and pivotally connected to the bracket 14 by a horizontal pivot pin 23 for 70 engagement with the lock shoulder 19 to lock the storm sash 11, when closed, to the window frame 9. On the upper edge of the detent 22 is a finger piece 24 by which said detent may be released from the lock shoulder 19 against the tension of a coiled spring 75 25 compressed between said detent and the bottom of the recess 21. In closing the storm sash 11, the detent 22 engages the ear on the sill bracket 13 having the lock 80 shoulder 19 and is cammed thereover for interlocking engagement with said lock shoulder, as shown in Fig. 3.

The lower end of the rod 15 is removably seated in a vertical bore 26 formed in the top 85 of the sash bracket 14 and its upper end is bent laterally to afford a foot 27, which rests upon the adjacent stile of the storm sash 11 and is secured thereto by a screw 28. One end of the link 16 is pivotally and adjustably attached to the rod 15 by a longitudinally split clamping sleeve 29 slidably mounted on said rod with freedom for turning movement thereon. This clamping sleeve 90 29 is provided with a pair of laterally spaced ears, between which the split in said sleeve extends, having aligned bores through which is inserted a thumb nut equipped draw bolt 30. The respective end of the link 16 extends between the ears on the clamping 95 sleeve 29 and is provided with a bore through which the draw bolt 30 extends and pivotally connects said link to the clamping sleeve. The distance between the ears on the clamping sleeve 29 is such as to permit 100 free pivotal movement of the link 16 thereon when said sleeve is frictionally clamped in different adjustments on the rod 15 by the draw bolt 30.

The other end of the link 16 is pivotally 110

and detachably secured to the sill bracket 13 by a lock pin 31, rigidly secured to the free end of a leaf spring 32 attached to said link. This lock pin 31 is arranged to extend 5 through alined bores in the ears of the sill bracket 13 and link 16 which is located between said ears. To separate the improved sash stop and fastener, it is only necessary to withdraw the lock pin 31 sufficiently by 10 bending the spring 32 laterally to release the link 16 and thereby permit the storm sash to be detached from the window frame.

Obviously, the storm sash 11 may be held in different open positions by adjusting the 15 clamping sleeve 29 on the rods 15. The above described sash stop and fastener is especially designed to securely hold a storm sash when open so that the wind cannot lift the sash and thereby separate or break 20 its supporting hinges. Said invention also securely holds the storm sash when open so that it will not rattle. By removably mounting one end of the rod 15 in the sash bracket 14, said rod may be easily separated therefrom for the application or removal of the 25 clamping sleeve 29 therefrom.

What I claim is:

A sash stop and fastener comprising a bracket applicable to a window frame and a rod applicable to a window sash, a longitudinally split clamping sleeve slidably mounted on said rod and having a pair of laterally spaced ears between which the split in said sleeve extends, a draw bolt extending through alined bores in said ears for frictionally securing said sleeve to the rod, a link having one of its ends inserted between the ears on the clamping sleeve and pivotally connected thereto by said draw bolt, and a flat spring carried by the other end of the link and having a lock pin adapted to be inserted through alined bores in the respective end of said link and bracket for pivotally and detachably connecting said link to the bracket. 30 35 40 45

In testimony whereof I affix my signature in presence of two witnesses.

EMIL F. BEHRENDT.
